UNITED STATES PATENT OFFICE.

FREDERICK WENDLING, OF EDMONTON, ALBERTA, CANADA.

VALVE-FACING TOOL.

Application filed June 26, 1923. Serial No. 647,832.

To all whom it may concern:

Be it known that I, FREDERICK WENDLING, a citizen of the United States, and a resident of Edmonton, in the Province of Alberta and Dominion of Canada, have invented a new and Improved Valve-Facing Tool, of which the following is a full, clear, and exact description.

The present invention relates to new and useful improvements in hand-operated tools, and it pertains more particularly to a tool especially adapted for use in refacing valves of the type employed in internal combustion motors, pumps, and the like.

It is one of the objects of the invention to provide a hand-operated tool which may be employed for facing internal combustion motor valves.

It is a further object of the invention to provide a new and improved mechanism for adjusting the valve to operative position.

With the above and other objects in view, reference is had to the accompanying drawings, in which—

Figure 1 is a plan view of a tool constructed in accordance with the present invention;

Fig. 2 is a view in side elevation thereof;

Fig. 3 is a transverse sectional view taken on the line 3—3 of Fig. 1, and

Fig. 4 is a transverse sectional view taken on the line 4—4 of Fig. 1.

Referring more particularly to the drawings, the device comprises a base 5, which is preferably of rectangular form. Rigidly secured to the base 5, are two right-angular members 6, each being formed with a base portion 7 and a vertical flanged portion 8. Each of the vertical flanged portions 8 of the right-angular members 6 is notched, as at 9, and the purpose of such notches will be hereinafter more fully described. Each of these right-angular members 6 is secured to the base by bolts 10, or the like.

Secured to the flange 8 of one of the right-angular members 6, by means of a bolt 11, is a block 12, said block carrying a cutter 13. The cutter 13 is mounted in a cut-out portion in the block 12, such cut-out portion being designated by the reference numeral 14. For adjustably securing the cutter 13 in the cut-out portion 14, a bolt 15, or the like, is employed.

The block 12 is provided with an elongated slot 16, through which the bolt 11 passes, and this construction provides for adjust-

ment of the block 12 transversely of the base 5 of the tool.

Adjustably mounted on the base 5, by means of a screw or bolt 17, is a plate 18, which plate is provided with a slot 19 to receive said bolt or screw 17. This plate 18 has a vertical extension 20, with which a screw-threaded bolt 21 has engagement, and said bolt 21 is provided with a centering head 22, the purpose of which will be hereinafter described. This bolt 21 is further provided with an operating handle 23.

Connecting the flanges 8 of the right-angular members 6 is a transverse bar 24, and slidably mounted on said transverse bar 24, is a yoke member 25. Secured to each of the arms of the yoke member 25, is an arm 26, and each of these arms 26 is provided with a hooked end 27. Carried by the yoke member 25, is a bolt 28, and said bolt lies in the notch 29 formed in the bar 30, which connects the rear end of the right-angular members 6. This bolt 28 is loosely mounted in the yoke member 25, and having threaded engagement with the bolt 28, is a wing nut 31, by means of which the yoke 25 and the arms 26 carried thereby are moved transversely of the base 5.

The reference character 32 designates a valve and said valve has the ordinary valve stem 33. 34 designates a handle or crank member which is adapted to be secured to the valve stem by means of a nut 35, or the like.

The device operates in the following manner:

The valve stem 33 of the valve 32 is positioned in the notches 9 of the flanges 8 of the right-angular members 6. After this is done, the hook ends 27 of the arms 26 are engaged with the valve stem, and the wing nut 31 is tightened on the screw-threaded bolt 28. This action moves the yoke member 25 and the arms 26 in such a manner that the hook ends 27 of said arms 26 pull the valve stem into the notches 9 of the flanges 8 of the right-angular members 6, as shown in Fig. 4. After this has been done, the block 12 is adjusted so that its cutter 13 will engage the face of the valve 32, and the centering head 22 of the bolt 21 is then engaged with the valve head to maintain the same in proper position.

After the foregoing adjustments have been made, the cutter 13 is adjusted, and by a turning of the nut 31, the valve 32 is se-

curely held in position relative to the cutter 13. The handle 34 is now attached to the valve stem and serves the means by which the valve is rotated in the presence of the 5 cutter 13. It will be noted that the cutter 13 has an angularly disposed cutting edge, and by changing the cutters the desired degree of pitch may be given the valve face.

From the foregoing it is apparent that 10 the present invention provides a new and improved hand-operated tool for facing or refacing valves, and that by the construction employed the valves may be cut with faces of different pitch, and faces in the 15 proper plane and true with respect to the valve stem may be obtained.

What is claimed is:

1. A valve facing tool comprising a base, notched flanged members carried by said 20 base and constituting a work support, a yoke member mounted for sliding movement between the flanged members, said yoke member having work-engaging hook portions, and means for moving the yoke member relative to the flanged members to cause the 25 work to engage the notches of the notched flanged members.

2. A valve facing tool comprising a base, a plurality of notched members carried by said base and constituting a work support, 30 a yoke member having hooked ends to engage the work and maintain the same in engagement with the notched members, and means for moving said yoke member relative to said notched members.

3. A valve facing tool comprising a base, a plurality of notched members carried by said base and constituting a work support, a yoke member having hooked ends to engage the work and maintain the same in 40 engagement with the notched members, and means for moving said yoke member relative to said notched members, said means comprising a cross bar connected to the notched members, said cross bar having a 45 notch formed therein, a screw-threaded member carried by the yoke member, and a nut having threaded engagement with the screw-threaded member and engaging the said cross bar and moving the yoke relative 50 to the notched member upon movement of the nut on the screw-threaded member.

FREDERICK WENDLING.
